UNITED STATES PATENT OFFICE.

THADDEUS GALVIN, OF DETROIT, MICHIGAN.

CHAFING-IRON.

No. 829,005.

Specification of Letters Patent.

Patented Aug. 21, 1906.

Application filed June 10, 1905. Serial No. 264,685.

To all whom it may concern:

Be it known that I, THADDEUS GALVIN, a citizen of the United States, residing at Detroit, in the county of Wayne and State of Michigan, have invented certain new and useful Improvements in Chafing-Irons, of which the following is a specification, reference being had therein to the accompanying drawings.

10 The invention relates to new and useful improvements in chafe-irons for vehicles; and it consists in the construction of a chafe-iron comprising a bifurcated bracket, sockets at the end of the furcations, one of the sockets being detachable, a roller journaled in the sockets, and a spring-block bearing against the roller between the sockets, and, further, in such a chafe-iron comprising a securing-plate to which the bifurcated bracket is angularly adjustably secured and in the construction, arrangement, and combination of the parts, as more fully hereinafter described, and particularly pointed out in the claims.

15 In the drawings, Figure 1 is a perspective view of my improved chafe-iron. Fig. 2 is a horizontal section through the spring-barrel, showing the spring-pressed block bearing against the roller.

20 A is the securing-plate, provided with suitable apertures *a*, by means of which it may be secured to the side of the vehicle in the well-known manner of securing chafe-irons to vehicles. This securing-plate I provide at one side with a lateral extension *B*, on which is provided the notched circular bearing *C*.

25 D is a bracket having a complementary notched circular bearing *E*, adapted to engage the bearing *C* of the securing-plate and to be angularly adjustably secured thereto by means of a clamping-bolt *F*, which passes through both members. The bracket *D* is a bifurcated bracket and has the furcations *G* *G'*. The furcation *G* has formed integral therewith the cylindrical socket *H*. The furcation *G'* has detachably secured to it a complementary cylindrical socket *H'*, the socket having the separated lugs *b* extending on each side of the furcation *G'* and detachably secured in position by means of a clamping-bolt *c*.

30 On the bracket *D* and between the furcations thereof is a barrel *I*, in which is secured the block *e*, having a pin *f* engaging a counterbore *h* in the bracket. Surrounding the pin and beneath the block *e* is a spring *i*, which tends to press the block *e* outward and against the middle portion of a roller *J*, which is journaled at its ends in the sockets *H* *H'*.

35 The parts being thus constructed, the securing-plate *A* being secured to the under side of the vehicle in proper position, so that the edge of the carriage-wheel when in turning will strike the roller *J*, the roller will rotate in the sockets *H* *H'* as the wheel rubs over it and reduces the wear and also materially prevents the unpleasant noise ordinarily made when the wheel scrapes over a stationary chafe-iron. In case the roller *J* is cut by the wheel it can be removed to permit a new one to be inserted by detaching the socket *H'*. The spring-pressed block *e* pressing against the roller prevents rattling. The adjustable connection between the supporting-plate *A* and the bracket *D* permits of adjusting the roller to any desired angle, so that the wheel will strike more nearly at right angles than if it were a solid piece and at the same time permits the securing-plate to be secured parallel to the longitudinal sides of the vehicle.

40 What I claim as my invention is—

1. In a chafe-iron for vehicles, the combination, of a bifurcated bracket, sockets at the ends of the furcations, a roller journaled therein, a barrel on the bracket intermediate the furcations, and a spring-pressed block therein bearing on the roller.

45 2. In a chafe-iron for vehicles the combination with a supporting-plate secured to the vehicle, of a bracket, a single pivot-bolt for angularly adjustably securing said bracket to said plate, a roller journaled in the bracket, a barrel secured to said bracket, and a spring-pressed block therein, for the purpose described.

50 3. In a chafe-iron for vehicles the combination with a supporting-plate, of a bifurcated bracket angularly adjustably secured thereto, a roller journaled in the furcations, a barrel secured between the furcations and a

spring-pressed block therein, for the purpose described.

4. In a chafe-iron for vehicles the combination with a bifurcated bracket, of an integral socket member on one furcation, a socket member detachably secured to the other furcation, a roller journaled at its ends in said sockets, a barrel secured to the

bracket and a spring-pressed block in said barrel, for the purpose described. 10

In testimony whereof I affix my signature in presence of two witnesses.

THADDEUS GALVIN.
